No. 877,908.

PATENTED FEB. 4, 1908.

G. W. COLLIN.
REDUCING VALVE.
APPLICATION FILED AUG. 8, 1907.

UNITED STATES PATENT OFFICE.

GEORGE W. COLLIN, OF MANSFIELD, OHIO.

REDUCING-VALVE.

No. 877,908.

Specification of Letters Patent.

Patented Feb. 4, 1908.

Application filed August 8, 1907. Serial No. 387,704.

To all whom it may concern:

Be it known that I, GEORGE W. COLLIN, a citizen of the United States, and resident of Mansfield, in the county of Richland and State of Ohio, have invented certain new and useful Improvements in Reducing-Valves, of which the following is a specification.

This invention refers to reducing valves and especially to steam pressure reducing valves and has for its purpose to generally improve existing types of valves, and more particularly to produce an improved type of steam pressure reducing valve which is especially applicable for locomotive use and to obtain a simple construction of valve that will operate quickly, effectively and have perfect drainage. In the production of automatically operated valves of this sort employing a valve that is actuated by steam alone, I find it desirable to introduce the steam so as to evenly distribute its pressure against all sides of the valve to prevent the same from binding and failing to operate. Also to locate the steam port from high pressure side of valve to auxiliary valve upon the introductory or inlet side of valve, and further to provide for the introduction of such steam at different points or sides of the auxiliary valve chamber; and finally to provide such auxiliary valve with a pivotal stem connection to insure its perfect seating.

With the above and other minor objects in view, I have devised the simple and novel construction shown upon the accompanying sheet of drawings forming a part of this specification, upon which similar characters of reference denote like or corresponding parts throughout the several figures, and of which,

Figure 1, shows a central vertical longitudinal sectional view through one of my improved valves complete. Fig. 2, is a transverse cross section taken on line 2—2 of Fig. 1. Fig. 3, is a cross section through auxiliary valve taken on line 3—3 of Fig. 1.

Referring in detail to the characters of reference marked upon the drawings A represents the main casing as a whole, which obviously may be cast in one piece and bored, tapped and finished as required. The upper end portion of this casting contains a chamber that is inclosed by a detachable screw plug H¹.

B¹ represents a double piston valve which

is mounted within the casing, and comprises a large piston D, which fits the bore in which it reciprocates and divides the same into two chambers D¹ and I¹, the latter being connected with the steam inlet. The valve C 60 connects with the piston D and serves to engage seat C¹ surrounding the port V in bottom of chamber I¹. Beneath the said chamber I¹ is located a cushion chamber E¹ which is provided with a port F that is 65 adapted to be opened and closed by the lower piston F¹ contained upon the winged stem E of the valve.

The steam is admitted to the chamber I¹ through the nipple A¹, and against the splitter I located central of inlet which as will be seen is designed to divide the impact of steam against the piston valve B¹, thus insuring an even or balanced operation of the same. Through the splitter I, as I term it, passes 70 the vertically located port J¹ leading from the chamber D¹ to auxiliary valve chamber V¹ the lower part of said port being also divided as at W to introduce the steam against the auxiliary valve from two sides. 80 The auxiliary valve chamber V¹ is also inclosed by a removable cap O, which may be detached for cleaning or repairs. A bushing L¹ contained within the valve chamber serves as a guide for the slide rod L and to which 85 the small end W¹ of auxiliary valve K is pivotally connected by means of a pin K² as shown in detail Fig. 3. The larger stem M¹ of valve is slidably mounted in bearings N and N² of casing, the latter being a narrow 90 bridge extending across the diaphragm chamber X which is thus consequently open into low pressure side K¹ of valve. A spring M mounted upon the slide rod L intermediate of bushing L¹ and auxiliary valve L obviously 95 serves to hold the latter closed against its seat when not opened by the larger spring Q permitted by reduced pressure in system.

The end of auxiliary stem M¹ contacts with center of diaphragm N¹ which is held in place 100 by a bonnet P screwed to the hub of casing. This bonnet is provided with a tubular extension Q¹ which forms an inclosure for the diaphragm spring Q before mentioned. The ends of the said spring Q are provided with 105 hubs P¹ and R¹ at opposite ends, the former to engage the diaphragm while the latter is engaged by an adjusting screw R to be secured in position by lock nut S.

The operation of my valve is as follows: 110

Steam is admitted through the inlet A¹ which in practice is connected with boiler, and is divided by the splitter I, to divide the impact of steam on valve in high pressure chamber 5 I¹. From there the steam escapes through port D² of piston D to upper chamber D¹ and from here to the port J¹ when auxiliary chamber V¹ is likewise filled. The tendency of the steam pressure under these conditions is obviously to hold both the piston valve and auxiliary valve closed. A manual operation of the screw R tends to compress the spring Q, the diaphragm, forcing the auxiliary valve K open allowing an escape of steam from chamber 10 D¹ through passage J¹ and chamber V¹, reducing the pressure in upper chamber D¹ causing the pressure in chamber I¹ to lift the piston valve from its seat thus allowing a free flow of steam through the low pressure side of 15 valve to system. When the system thus becomes filled to the pressure desired, the service system will act upon the diaphragm and force the same out against its spring, leaving the auxiliary valve free to close, 20 shutting off the escape of steam from upper chamber D¹ causing it to become filled and the valve body to settle down upon its seat and close the main passage. The valve thus remains closed until the system pressure 25 becomes reduced whereupon the same operation is repeated, and so on, the valve repeats its operations from time to time and sustains the system pressure.

Having thus described my invention what 30 I claim and desire to secure by Letters Patent is:—

1. In a valve of the class described, the combination with a casing having a steam chamber therein, a valve mounted in the 35 casing and carrying a piston, a steam inlet in the side of the casing having a central transverse divisional wall arranged thereacross to introduce the incoming steam from opposite sides against and intermediate the piston and valve.

2. In a valve of the class described, the combination with a casing having a high pressure chamber, a cushion chamber and low pressure chamber, combined piston 40 valve mounted in the casing and including a piston and port closing valves to operate intermediate the several chambers, a steam inlet inside of casing having a central divisional wall to divide the steam and introduce it to high pressure chamber on opposite 45 sides of and intermediate of, piston and valve, a port extending through the said wall

and connecting the high and low pressure chambers.

3. In valve of the class described, the combination with a casing having a high pressure chamber, a cushion chamber and low pressure chamber, a combined piston and valve mounted in the casing and having a piston and port, closing valves to 50 operate intermediate the several chambers, a steam inlet inside of casing having a central divisional wall to divide the steam and introduce it to high pressure chamber on opposite sides of and intermediate of piston and valve, an auxiliary valve, a port extending through the said divisional wall and connecting the high pressure chamber with auxiliary valve chamber and a diaphragm for operating said auxiliary 55 valve.

4. In a valve of the class described, the combination with a casing having a steam chamber therein, a double valve mounted in the casing and carrying a piston, a steam 60 inlet provided with a transverse divisional wall, and extended side ports which enter the chamber opposite but central of the valve stem in a way to equalize the pressure thereagainst.

5. In a valve of the class described, the combination with a casing having high and low pressure chambers, a cushion chamber, a combined piston and double valve mounted in the casing, an auxiliary valve chamber, a port leading from high pressure chamber to auxiliary valve chamber, an auxiliary valve, a slide rod pivotally connected to said auxiliary valve, a spring encircling the said rod and operating against the auxiliary 65 valve, and a diaphragm to manipulate the auxiliary valve against the action of the spring.

6. In a valve of the class described, the combination with a casing having a steam 70 chamber therein, a double valve mounted in the casing and carrying a piston, a steam inlet provided with a transverse divisional wall, an auxiliary valve adapted to open or close the main valve and a piston actuated diaphragm for operating the auxiliary valve.

Signed at Mansfield, in the county of 75 Richmond and State of Ohio, this 29th day of July, A. D., 1907.

GEORGE W. COLLIN.
